UNITED STATES PATENT OFFICE

ONESIME H. LE COMPTE, OF OKLAHOMA CITY, OKLAHOMA.

AUTOMATIC TRAIN-PIPE COUPLING

Application filed September 8, 1925. Serial No. 55066

My present invention relates to train pipe couplings for automatically coupling of the brake, signal and steam pipes of railway cars, freight and passenger, including street rail-way cars and motor bus trains, and, it is a distinct and practical improvement to overcome certain practical objections to, and defects in, past and present types of train pipe couplings, and, has for an object to improve the construction of automatic train pipe couplings which will effect simultaneously with the coupling of the car couplers, a positive leak proof automatic coupling of all train pipes, thus avoiding the necessity of persons going between the cars to effect coupling the train pipes.

With the above and other objects in view, as will be apparent from the description hereinafter set out, the invention consists in the novel features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1, is a side elevation of a portion of two draft couplers connected and each carrying an automatic train pipe coupler embodying the features of my invention.

Fig. 2, is a rear end elevation of one of the coupler manifolds.

Fig. 3, is a top plan view thereof.
Fig. 4, is a detail, actual size, of the

Fig. 4, is a detail, actual size, of the forward end of one of the coupling pipes, the gasket holder, the gasket and the adjusting nut, showing the gasket and its holder in a slightly advanced position from that shown in Fig. 6.

Fig. 5, is a front elevation of one of the complete train pipe couplings depending from a draft coupler.

Fig. 6, is a longitudinal vertical sectional view of one of the train pipe couplings.

Referring to the drawings, the reference character 1 represents a pair of like car coupler heads, preferably, although not necessarily of the type which are rigidly united when in coupled relation as far as longitudi-

nal movement is concerned, but capable of swinging movement with relation to their respective draw-bars to permit cars to which they are a part, of taking short sharp curves, as well as long curves without affecting the train pipe coupling which is the subject matter of this application.

A pair of opposed downwardly directed arc shaped wings 2 are employed to provide a socket member and they are preferably integral with the bottom wall of the coupler heads 1, and these wings have their lower ends spaced apart to provide a lower longitudinal passage 3. The inner faces of the opposed wings are inclined so as to form a tapered horizontally disposed socket opening 4 wider in diameter at its forward end than at its rear end, as will be apparent from Figs. 5 and 6. The rear end of the upper half of the socket opening 4 is closed by means of a rear stop wall 5 which is integral with the wings 2 and the bottom wall of each coupler 1 and the wall 5 is provided with a bolt receiving opening 6.

The reference character 7 represents a manifold. The manifold is a hollow member having its upper end provided with a suitable enlarged head 8 having a tapered peripheral face 9. The tapered head 8 is receivable in the tapered socket opening 4. The front and rear walls 10 and 11 of the manifold are provided with aligned openings 12 in the head section 8 for receiving a suitably headed bolt 13 which also passes through the opening 6 in the rear stop wall 5 and provided with a split washer 14 and the securing nuts 15 and 16 for locking the manifold against longitudinal displacement in the tapered socket 9. A suitable set screw 17 provided with a lock nut 18 is carried by each wing 2 in opposed relation for engaging the tapered peripheral face of the head 7 to lock the manifold head against rotary displacement after it has been adjusted to the proper position in the socket 9. The bolt 13 and the set screws 17, it will be observed hold the manifold in any adjusted position, as will be apparent from Figs. 5 and 6.

The front and rear walls of the manifold 100

7 are also provided with the opposed sets of openings 19, 20 and 21, which openings are arranged one below the other in suitable spaced relation and in alignment, preferably with the center of the head 8, as shown in Figs. 5 and 6.

The openings 19, 20 and 21 are adapted to receive the horizontally disposed coupling pipes 22, 23 and 24, respectively, which pipes are screw threaded at each end and such screw threaded ends are designed 25 and 26. A coupling pipe socket member 27 having a reduced internally screw threaded nipple 28 has screw threaded engagement 15 with the forward screw threaded end 25 of each coupling pipe 22, 23 and 24, as clearly shown in Fig. 6. The nipple 28 of each coupling pipe socket member 27 is also externally screw threaded, as at 29, to receive 20 a suitable jam nut 30, the rear face of which is adapted for engagement with the front face of the front wall 10 of the manifold, as clearly shown in Fig. 6. When the socket member 27 is in its rearwardmost position, 25 as shown in Fig. 6, the front face of the jam nut 30 will engage the shoulder 31 of the coupling pipe socket member 27.

The forward end of each coupling pipe socket member 27 is provided with a socket 30 opening 32 having a slightly tapered wall for rendering such opening greater in diameter at its rear end than at its forward end, as will be apparent in Figs. 4 and 6 of the drawings.

35 A suitable packing member or gasket coupling terminal 33 is receivable in the rearwardly and outwardly tapered socket opening 32 of each coupling pipe socket member 27, as clearly shown in Fig. 4, and are each 40 provided with a central opening 34 for receiving a metallic sleeve 35 having a bore of the same diameter as the bore of the coupling pipes 22, 23 and 24, respectively. The train pipe coupling 24, which is preferably 45 used for steam, is preferably larger in diameter than the pipes 22 and 23, which are used for air, for the air brakes and air signals, respectively.

50 The rear screw threaded end of each coupling pipe 22, 23 and 24, is provided with the jam nut 36 and the lock nut 37 to prevent longitudinal displacement of the coupling pipes relative to its respective manifold and the forward face of its respective car coupler.

55 The rear screw threaded ends 26 of each coupling pipe 22, 23 and 24 is connected with a plug member 38 to which the train pipes, such as air brake, air signal and steam and 60 designated 39, 40, and 41, respectively, are suitably connected, as will be apparent from Figs. 1 and 6.

65 Each manifold 7 is provided at the base of the head 8 thereof with the opposed suitable shoulders 42 which limit extreme ad-

justment movements of the manifold relative to the coupler head by coming into contact with the lower ends of the arc shaped socket walls 2, as will be apparent from Fig. 5, of the drawings.

70 It will be here observed that the forward ends of the gasket coupling terminals extend a suitable distance beyond the front plane of their gasket holders, or sockets, so as to allow for suitable amount of compression of the same during coupling operations to provide tight joints or connections between the engaged gasket terminals when two cars are coupled together to prevent air and steam leakage and to provide perfect electrical contacts when electric circuits are employed.

75 In cases where the gasket coupling terminals have become worn or otherwise shortened in length, it will be evident, from Figs. 4 and 6, of the drawings, that the lock nut 37, 80 and the jam nut 36 are loosened or backed upon the pipes 22, 23 or 24 and then the adjusting jam nut 30 is backed up on the screw threaded nipple 28 of the socket member 27 the distance that it is desired to advance 85 the gasket coupling terminal 33, as clearly illustrated in Fig. 4, so as to bring its outer face into the proper relation with the front plane of the coupler head so that when the 90 coupler heads are connected there will be a 95 tight union or joint formed between two opposed engaged gasket coupler terminals 33, as clearly shown in Fig. 1.

95 From the foregoing description and the 100 illustrations, it is apparent that I provide extremely simple means of inexpensive construction which will operate or function, with absolute certainty under all ordinary conditions, to automatically couple all of the train 105 line pipes with the coupling of the coupler heads, such as the air pipes for braking and 110 signal purposes, the steam pipes for heating purposes and conductor terminals where electric circuits are employed for lighting, heating and cooling purposes, and, that I further provide a train pipe coupling which 115 contacts with the coupler heads as a distinct structure and is provided with means for their ready relation, which means includes bolts, 120 set screws, jam nuts and lock nuts for each 115 train pipe coupling for adjusting the train pipe coupling elements with relation to the car coupler heads and each of the train line 125 coupling pipe elements, especially the gasket coupling terminals with relation to the manifold and the front face of their respective 126 coupling head.

130 The many advantages of the herein described invention will readily suggest themselves to those skilled in the art to which it appertains.

I do not wish to be understood as having limited myself to the details of construction shown and described, but desire to have it understood that the invention I have shown 135

in the drawings is merely illustrative, as it is manifest that various minor changes may be made in the exact construction and particular arrangement of parts without departing from the spirit of my invention, hence I reserve the right to make any such changes, or modifications as may fairly fall within the scope of the appended claims when fairly construed.

10 What I claim is:

1. In a train pipe coupling, in combination with a draft coupler, a socket member depending from the lower face of the draft coupler and having a conical socket, said socket member having its wall provided with a cutaway portion at its lower side, a stop wall at the rear end of said socket having an opening therein, a manifold member having a conical shaped head receivable in the aforesaid socket and a body portion directed downwardly from said head and passing through the cutaway portion of the socket member, locking means carried upon opposite sides of the socket member and engaging the conical head, shoulders at the upper end of said body to limit rotary displacement of said head within its socket to prevent displacement of said manifold member from an adjusted position, and a plurality of train pipe coupling connections adjustably carried by said manifold member.

2. In a train pipe coupling, a pipe externally screw threaded at opposite ends adapted to be supported by a manifold member and having its screw threaded ends projecting beyond opposite faces of the manifold member, a socket member having a rearwardly tapered end socket, an internally and externally screw threaded nipple forming a part of the socket member connected to the outer screw threaded end of said pipe, an adjusting jam nut having screw threaded engagement with the external screw threads of said nipple and engaging the outer face of the manifold member, a jam nut having screw threaded engagement with the inner screw threaded end of the pipe and engaging the opposite face of the manifold member, a lock nut having screw threaded engagement with the inner screw threaded end of the pipe and engaging said jam nut, a compressible gasket coupling terminal having a central opening receivable in the rearwardly tapered end socket of the socket member, a metallic sleeve within the opening of said gasket coupling terminal having a bore of the same diameter as that of the aforesaid pipe and in registered alignment therewith and a portion of both the gasket coupling terminal and its metallic sleeve projecting outwardly beyond the outer face of the socket member.

3. In a train pipe coupling, in combination with a draft coupler, a socket member depending from the lower face of the draft coupler and having a horizontally disposed

conical socket, said socket having its wall provided with a cutaway portion at its lower side to provide a longitudinal passage, a hollow manifold member having a cylindrically shaped head mounted in the aforesaid socket and a body portion directed downwardly from said head and passing through said passage which is wider than the depending portion of the manifold, means for locking the manifold in an adjusted position against lateral rocking displacement, a plurality of coupling pipes passing through openings in said manifold, a holder carried by the forward end of each coupling pipe, a gasket for each holder, means for longitudinally adjusting said pipes to bring the gaskets to a position that will cause the front faces thereof to assume a position in a plane with the front face of their respective draft coupler face when compressed and means for locking said coupler pipes in their adjusted positions and against longitudinal displacement.

4. In a train pipe coupling, in combination with a draft coupler, a socket member depending from the lower face of the draft coupler and having a horizontally disposed conical socket, said socket having its wall provided with a cutaway portion at its lower side to provide a longitudinal passage, a stop wall at the upper rear end of said socket, a fastening member passing longitudinally through the head of said manifold and an opening in said stop wall, laterally disposed fastening devices for holding the manifold head against rotary displacement, a coupling pipe carried by said manifold member, a holder member having screw threaded engagement with the forward end of said pipe, a gasket carried by said holder, a ring member carried in the opening of said gasket, a nut having screw threaded engagement with the rear end of said holder and having its rear face in engagement with the front face of the manifold member, and means having screw threaded engagement with the rear end of the coupling pipe and engagement with the rear face of the manifold member to prevent longitudinal displacement of the coupling pipe with relation to the manifold.

5. In a train pipe coupling, in combination with a draft coupler, a socket member depending from the lower face of the draft coupler and having a horizontally disposed conical socket, said socket having its wall provided with a cutaway portion at its lower side to provide a longitudinal passage, a hollow manifold member having a cylindrically shaped head mounted in the aforesaid socket and a body portion directed downwardly from said head and passing through said passage which is wider than the depending portion of the manifold, means for locking said manifold head against longitudinal displacement with relation to the draft coupler, means for locking the manifold head against rotary

displacement, a plurality of coupling pipes carried by said manifold member, a holder adjustably carried at the forward end of each coupling pipe, a gasket carried by each holder with its front face normally slightly in advance of the plane of the front face of the draft coupler and means for locking said coupler pipes against longitudinal displacement.

6. In a train pipe coupling, in combination with a draft coupler, a socket member depending from the lower face of the draft coupler and having a horizontally disposed conical socket, said socket having its wall provided with a cutaway portion at its lower side 10 to provide a longitudinal passage, a hollow manifold member having a cylindrically shaped head mounted in the aforesaid socket and a body portion directed downwardly from said head and passing through said passage which is wider than the depending portion of the manifold and means to prevent lateral rocking displacement of said manifold from an adjusted position.

7. In a train pipe coupling, in combination with a draft coupler, a socket member depending from the lower face of the draft coupler and having a horizontally disposed conical socket, said socket having its wall provided with a cutaway portion at its lower side 20 to provide a longitudinal passage, a hollow manifold member having a cylindrically shaped head mounted in the aforesaid socket and a body portion directed downwardly from said head and passing through said passage which is wider than the depending portion of the manifold, means to prevent longitudinal displacement of the manifold relative to the socket and means to prevent rotary movement of the head within the socket from 30 an adjusted position.

8. In a train pipe coupling, in combination with a draft coupler, a socket member depending from the lower face of the draft coupler and having a horizontally disposed conical socket, said socket having its wall provided with a cutaway portion at its lower side 40 to provide a longitudinal passage, a hollow manifold member having a cylindrically shaped head mounted in the aforesaid socket and a body portion directed downwardly from said head and passing through said passage which is wider than the depending portion of the manifold, the body of the manifold depending from the head having its 50 front and rear walls provided with a plurality of spaced, opposed vertically aligned openings adapted to receive train pipe connections, stop shoulders at the junction of the head with the depending body portion 60 of the manifold, means to prevent longitudinal displacement of the manifold head in the socket member and means to prevent rotary movement of the manifold head in the socket member.

9. In a train pipe coupling, in combination

with a draft coupler, a socket member depending from the lower face of the draft coupler and having a horizontally disposed conical socket, said socket having its wall provided with a cutaway portion at its lower side 70 to provide a longitudinal passage, a hollow manifold member having a cylindrically shaped head mounted in the aforesaid socket, and a body portion directed downwardly from said head and passing through said passage which is wider than the depending portion of the manifold, means to prevent lateral rocking displacement of said manifold from an adjusted position, an externally screw 75 threaded pipe adapted to freely pass through opposed openings in the walls of the manifold, a socket member having an internally and externally screw threaded nipple connected to the forward end of said pipe, an adjusting jam nut carried by said nipple and engaging the manifold, a jam nut carried by the opposite end of said pipe and engaging the manifold, a lock nut carried by the pipe and engaging said jam nut, said socket member having a socket opening provided with a slightly tapered wall, a gasket coupling terminal disposed in said socket and extending beyond the front face of the socket member and a metallic sleeve within said gasket coupling terminal.

In testimony whereof, I have hereunto signed my name to the specification.
